CONTAINER FOR PACKAGING AND DISPLAYING GIRDLES

Henry N. Reuder, New York, N.Y., assignor to William Gluckin & Company, Inc., New York, N.Y., a corporation of New York

Filed Feb. 15, 1961, Ser. No. 89,394

4 Claims. (Cl. 206—7)

This invention relates to containers comprising two container parts, namely a product for girdle supporting part and a sleeve part, in which the first named part is arranged and coupled to form a unitary finished substantially sealed container. More particularly, the invention deals with a structure of the character described, wherein the main wall portions of the container parts have contracted side edges controlling positioning of the inner part in the outer or sleeve part of the container.

Still more particularly, the invention deals with a structure of the character described, wherein the inner part includes means for definitely gripping and holding end portions of a panty-type girdle, in connection with opposed side walls of said inner part.

The novel features of the invention will be best understood from the following description, when taken together with the accompanying drawing, in which the separate parts are designated by suitable reference characters in each of the views and, in which:

FIG. 1 is a view of the inner container part in open position, diagrammatically illustrating a panty-type girdle coupled therewith, with parts of the construction broken away.

FIG. 2 is a face view of the assembled container on a reduced scale.

FIG. 3 is an enlarged section on the line 3—3 of FIG. 2 showing only the container and illustrating parts of the construction in elevation, with parts broken away; and

FIG. 4 is a partial section on the line 4—4 of FIG. 2 on an enlarged scale and omitting the inner container part.

In the drawing, FIG. 1 shows the inner container part 10 in an extended position. This container part comprises two walls 11 and 12, generally of the same peripheral contour, in other words, having contracted edges 13 and 14, respectively, which join in a central narrow wall portion 15, forming the bottom wall of the container assemblage, as illustrated in FIGS. 2 and 3 of the drawing. This narrow bottom wall has, at its ends, extending flaps 16 which operate to retain side wall portions of a folded panty girdle 17 in position at the lower contracted end of the container assemblage. This will clearly appear from a consideration of FIG. 1 of the drawing.

The wall 11 has, at its upper end, a narrow top closure wall portion 18, including an integral closure flap 19. The flap 19 includes a projecting tongue 20 having foldable ears 21, the function of which will be later described, the ears 21 being foldable on the fold dotted line 23 and the closure wall 18 is foldable on the wall 11 on the dotted fold line 24.

The part 11 includes two slits 25 and 26, the slit 25 being generally U-shaped in form; whereas, the slit 26 is of an irregular contour, as clearly noted in FIG. 1, and these slits collectively form a garment retaining band 27 for support of the upper folded waistband portion 28 of the girdle in connection with the wall part 11.

The girdle, in the construction shown, is of the panty-type and includes the crotch insert portion 29, diagrammatically illustrated in FIG. 1 of the drawing, and the lower leg portions of the girdle include a plurality of garters, a pair of which are diagrammatically illustrated

2

at 30 and portions of other garters are indicated at 31, the latter being broken away to simplify the present illustration. The purpose of this is to illustrate attachment of the garters 30 to cutout garter engaging tab portions

5 32 fashioned integrally from the wall 12. The tab portions 32 include adjacent the fold lines 33 cutouts 34 for engaging the rounded heads 35 of conventional stocking engaging clasps of the garters. This construction serves to definitely position the lower leg portions of the

10 panty girdle on the wall 11, so that, when the inner part 10 is moved into the extended display position, as shown in FIG. 1 of the drawing, the girdle 17 will maintain a display position, substantially as diagrammatically illustrated in FIG. 1 of the drawing. The free end of the

15 wall 12 includes a supplemental closure flap 36 foldable on the line 37. This flap, in combination with the wall 18, forms a complete closure to the top flared end of the container assemblage, as will clearly appear from a consideration of FIG. 3 of the drawing.

20 No detailed description of the garter structure 30 is deemed to be necessary, except to the inclusion of the head 35 which establishes a definite engagement with the tabs 32 and, for this reason, no complete showing of the broken away garters 31 is deemed to be necessary. The lower leg portions of the panty girdle, in their folded relationship, are diagrammatically illustrated at 38, 38' in FIG. 1.

The other container part 39 is in the form of a tubular sleeve having a flared end portion 40 and a contracted end portion 41. Note FIG. 2 of the drawing. For purposes of description, the wall 42 of the container part 39 may be said to comprise the front wall; whereas, the wall 43, note FIGS. 3 and 4, may be said to comprise the back wall. One of the side walls of the sleeve 39, for example, the wall 44, note FIG. 4, includes an extending flap 45 secured to the wall 43 in support of the sleeve 39 in its assembled relationship.

The front wall 42 has, at its upper portion, upwardly flared slits 46 adapted to receive the ears 21 of the tongue 20 in coupling the container part 10 with the part 39, as clearly illustrated in FIG. 2 of the drawing.

In the showing in FIG. 3 of the drawing, part of the inner container 10 is shown in end elevation and part of the same is shown in section. It will be apparent that 45 the flaps 16 serve to hold or confine the foldable substantially central portion 17' of the girdle in position on the inner container part 10 when the walls 11 and 14 are folded on the fold lines 11', 14', indicated, in part, in FIG. 1 of the drawing in passing the inner container 50 part into the sleeve part 39 and, upon completing this operation, the flap 19, including the wall 18, is folded over the top of the assemblage and the ears 21 are coupled with the fold wall 42 by passage through the slits 46. This position of the complete assemblage provides a neat and finished package for shipment, storage and handling and, as a matter of fact, by utilizing attractive materials in the respective container parts, the package may be utilized in the storage of the garment in a dresser or other storage by the purchaser, the container 55 maintaining the garment in clean and desirable shape at all times until it is desired to use the same and, from time to time, the garment can be recoupled with the container to continue the well protective features in storage of the garment, particularly after laundering. It will also be understood that, in merchandising the garment, the inner part 10 can be moved into its extended position and the upper tongue 20, including the ears 21, can be utilized for hanging or other display support of the garment in conducting sales thereof.

60 In addition to the features previously mentioned, this packaging and displaying container further operates to 65 glamorize the display of the merchandise in removal of

the container with the garment thereon from the sleeve and then extending the two side walls of the container in displaying the full length of the garment, while still supported on the container part. This feature further substantially eliminates soiling of the garment by avoiding 5 extensive handling.

Having fully described my invention, what I claim as new and desire to secure by Letters Patent is:

1. A girdle packaging and displaying container, comprising an inner container part and an outer sleeve part in which the inner part is arranged, said inner part comprising two side wall portions joined by an intermediate coupling wall forming one end of the container part, said side wall portions having flared side edges, one of 10 said first named side walls having a pair of slits for engaging and retaining the upper folded waistband portion of a girdle thereon, said wall including an upper closure wall, a closure flap on said closure wall, said flap including a tongue having laterally extending ears, the other side wall of said inner container part having a 20 pair of integral tabs, the tabs including cutouts for operatively engaging a pair of garters at the lower portion of the girdle in definitely positioning the lower portion of the girdle on and retaining the same against displacement from said second side wall, and one wall of said sleeve 25 part having a pair of slits, through which the ears of said tongue on the first named side wall part pass in

15

coupling the inner container part in connection with said sleeve part.

2. A container as defined in claim 1, wherein the sleeve part includes contracted side walls conforming to the general contour of the flared side edges of the side walls of the container part.

3. A container as defined in claim 1, wherein the end wall joining the side walls of the container part include 10 extending side flaps for retaining the central portions of the girdle in position on the container part.

4. A container as defined in claim 1, wherein the second named side wall of the container part includes, at its end, a closure flap disposed within the first named closure flap.
